ROBERT E. READ, OF WHITE PLAINS, NEW YORK, ASSIGNOR TO INTERNATIONAL PAPER COMPANY, A CORPORATION OF NEW YORK.

PAPER-MAKING MACHINE.

Application filed January 6, 1927. Serial No. 159,253.

This invention relates to paper making machines and is particularly concerned with the means for establishing the travel of the paper web through the machine in starting 5 the operation of the machine in the first instance, or in reestablishing the travel of the web in the event of the breakage or parting of the same. It is customary in these operations to form a relatively narrow lead strip 10 on the web by incising the same longitudinally near one edge, and to start the travel of the lead strip through the machine, and when the travel of the same has become fully established, to gradually widen out the strip 15 to the full width of the web. In this operation there is a tendency of the lead strip to adhere to the rotary roll of the machine, with which it is for the time being in contact and thus fail to follow its proper course 20 through the machine. For instance in the travel of the strip through the presses, the strip is liable to adhere to and follow around with the upper press roll instead of passing to the conveying felt below, as it should. 25 The present invention is designed to overcome this objectionable action and to insure that, in the event of the lead strip adhering to the roll, it may be conveniently detached therefrom and directed to its proper path 30 of travel, and with this end in view the invention consists in the provision of a device associated with the roll in the machine to which there is a tendency of the lead strip to adhere, which device may be operated to 35 sever the adhering lead strip crosswise and cause its severed end to be lifted or turned away from the roll, and in combination with said device, a fluid blast device in position to direct its blast against the roll at such an 40 angle, and in such relation to the end of the lead strip, that the latter will be stripped from the roll and directed to its proper path of travel, in the particular application of the invention illustrated, to the conveying felt below. 45 The invention also consists of the method of establishing the travel of the paper web through the machine, involved in the operation of my improved mechanism. 50 In the specification to follow, the invention will be described in detail, and the novel features thereof will be pointed out in the appended claims.

In the accompanying drawings:

Fig. 1 is a side elevation of one of the

presses of a paper making machine showing my invention applied thereto.

Fig. 2 is a front elevation of the same.

Fig. 3 is a view similar to Fig. 1, but on an enlarged scale, to better indicate the angle 60 of impingement of the fluid blast against the roll.

Referring to the drawings:

In the accompanying drawings I have shown my invention by way of example in 65 connection with the upper press roll of one of the presses of a paper making machine, to insure the passage of the lead strip to the conveying felt passing between said roll and the lower press roll, but it will be manifest 70 to those skilled in the art that the invention is not limited to this particular part of the machine, but is applicable as well to other locations, for instance, to the rolls of 75 the calender stack, and to other parts or members of the machine to which the lead strip is liable to adhere.

The press unit shown comprises as usual an upper press roll 1, a lower press roll 2, and an endless conveyor felt or traveling 80 member 3 passing between said rolls and suitably guided by the usual guiding rolls, all as well known in this art.

In carrying out my invention, I provide a device for cutting or severing the lead 85 strip 4 of the paper web, which strip is shown as adhering to and as being carried upwardly on the upper press roll. This cutting device is in the present instance in the form of a finger 5 preferably made of 90 lignum vitae, and is provided with a cutting point 5^a adapted, when engaged with and drawn in a horizontal direction across the lead strip on the traveling roll, to cut the strip through transversely, the severed end 95 of the strip, on account of the continued travel of the roll, presenting an oblique line or edge. The cutting finger 5 is fixed to the inner end of an operating rod 6 mounted to slide horizontally in a fixed bearing 7 at the side of the press roll, which rod may also be turned in its bearing to swing the active end of the finger to and from the roll; and the outer end of the rod is provided with a handle 8 for positioning and operating 100 the cutter.

As a result of the mounting of the cutting finger as described, it may, by a turning motion of the handle 8, be swung in its bearing to adjust its cutting point into operative or 110

inoperative relation to the press roll, and by shifting the handle inwardly and outwardly, the finger may be first positioned at the inner edge of the lead strip and then drawn outwardly across the same and thereby cut the strip transversely, for the purpose presently to be described.

Arranged above the line of action of the cutting finger, so as to act on the end of the severed lead strip, is a fixed fluid blast device 9, in the form of a horizontal pipe 10 supplied with compressed air from a suitable source by a supply pipe 11 leading from the outer end of the pipe 10 and having a cut-off valve 11^a therein in order to enable the blast to be turned off or on as desired. In the present instance the pipe 10 is formed with a horizontal line of air nozzles 13 communicating with the interior of the pipe and directed towards the upper press roll, so that the jets of air issuing from the nozzles, will impinge against the roll in a horizontal line, which, by reason of the number and disposition of the nozzles extends the full width of the lead strip as best shown in Fig. 2. The angle of impingement of the line of jets on the roll, and the relation of said jets to the end of the lead strip severed by the cutter, is such that the air currents rebounding from the surface of the roll, will act to throw the severed end of the lead strip downwardly onto the conveying felt as shown in Fig. 1.

Under the normal conditions of operation of the paper making machine, with the paper web traveling its proper path, the air to the blast device is cut off, and the cutting finger is swung down away from the roll as shown by dotted lines in Fig. 1 and is drawn to its outer position as shown by full lines in Fig. 2. In the use of the mechanism, when the lead strip, previously formed on the web by incising the same longitudinally, adheres to and is carried upwardly with the upper press roll, the attendant first turns on the air to the blast device, then pushes the cutter to its inner position as shown by dotted lines in Fig. 2, and then by a turning motion of the handle, swings the active end of the finger into contact with the press roll, at a point just then drawn outwardly, with the result that its active cutting point engaging the lead strip, will sever the same transversely. At the beginning of the cutting action at the inner edge of the strip, the continued travel of the roll will force the adhering severed end against the cutter and said end will be thereby lifted and turned away from the surface of the roll, and the air currents from the nozzles rebounding from the surface of the roll, will act behind the lifted end of the strip and will peel the same from the roll, and at the same time throw the end of the strip down towards and on the conveying felt as shown in Fig. 1.

It will be observed on reference to Figs. 1 and 3 that the angle of impingement of the air jets to the surface of the roll is such that the air currents will rebound from the roll at a sharp acute angle, and this is a very important feature of the invention, since by reason of the particular angular relation of the air impingement shown, bringing about this sharp rebound of air currents, the adhering strip is removed from the surface of the roll and caused to follow the direction of movement of the conveying felt without liability of forming slack in the strip which would result, for instance, if the air currents were directed more toward the lower roll.

Each of the presses will preferably be equipped with my improved strip cutting and blast mechanism, and when the mechanism has been operated as described in connection with one press, the air blast of that press will be kept on until the travel of the strip has been established, as by entering between the rollers of the next press, whereupon the air to the first blast will be cut off; it being understood that with the improved mechanism applied at other points in the machine, the air blast is shut off just as soon as the travel of the lead strip is established and there is no further danger of the same passing out of its proper path.

In order that the blast device may be moved to an inoperative position after the travel of the lead strip has been established, so that there will be no danger of the obstruction of the travel of the strip, which might occur by reason of a slight slack in the strip which at times occurs where it passes between the rolls, I form the supply pipe 11 by which the blast device is supported, with a jointed coupling 14 as shown in Fig. 2, whereby the blast device may be swung up to an inoperative position as shown by dotted lines in said figure; and in order that when swung down again to its operative position it will be prevented from moving below its proper point, a stop device 15 is fixed to the machine frame in position to be engaged by the inner swinging portion of the pipe.

It will be manifest to the skilled mechanic that the various details of the mechanism as above described, may be modified and changed without departing from the spirit of the invention. For instance, the air pipe instead of being provided with projecting nozzles for the discharge of the air currents, may be formed with a continuous slit, or the pipe may be provided with a line of holes therethrough; and the detailed form of the cutter device may be variously modified, and likewise the manner of mounting the same, all of which changes and modifications will fall within the scope of the invention, which in its broader aspect as re-

gards the mechanism, involves the combination with means for severing the adhering lead strip, of a fluid blast to direct the severed end of the strip to its proper path of travel.

Having thus described my invention, what I claim is:

1. In a paper making machine, the combination of a rotary roll, a traveling member in position to receive the paper web from said roll, a cutting device operable to sever a lead strip on the roll, and a fluid blast device associated with said cutting device and in position to blow on the severed end of the strip and operating to carry it toward the traveling member.
  2. In a paper making machine, the combination of a rotary roll, a traveling member in position to receive the paper web from said roll, a cutting device operable to sever a lead strip on the roll, and a fluid blast device associated with said cutting device and in position to direct its blast against the roll at a point above the severed end of the strip, and at such angle that the blast in rebounding will act to carry the strip toward the traveling member.
  3. In a paper making machine, the combination of a rotary roll, a traveling member in position to receive the paper web from said roll, a cutting device operable to sever a lead strip on the roll, and a fluid blast device associated with said cutting device and in position to so impinge its blast against the roll, that the blast will rebound from the roll against the lead strip at an angle acute to its direction of impingement, and in a direction toward the traveling member.
  4. In a paper making machine, the combination of a rotary roll, a traveling member in position to receive the paper web from
- the roll, a cutting device operable to sever a lead strip on the roll along a line oblique to the direction of travel of the strip, and in such position that the continued travel of the roll will carry the severed end of the strip against the knife and lift said end from the roll, and a blast device associated with said cutting device and in position to impinge its blast against the roll at such point and in such direction, that the blast in rebounding will act on the lifted end of the strip and carry the latter toward the traveling member.
5. The method of establishing the travel of a paper web through a paper making machine, which consists in forming a lead strip on the web, severing the adhering lead strip on a rotary roll of the machine and lifting the severed end of said strip from the roll, directing a fluid blast against the lifted end of the strip to cause the strip to be carried by the blast to its proper path of travel, and when the travel of the lead strip has been established, widening said strip to the full width of the web.
6. In a paper making machine, the combination of a rotary roll, a traveling member in position to receive the paper web from said roll, a cutting device operable to sever a lead strip on the roll, a fluid blast device in position to act on the severed end of the strip to carry it toward the traveling member, and a supply pipe connected with the fluid blast device to supply fluid under pressure thereto, said supply pipe being formed with a jointed coupling to enable the blast device to be swung to an inoperative position relative to the roll.

In testimony whereof I have affixed my signature hereto.

ROBERT E. READ.
